UNITED STATES PATENT OFFICE

2,377,652

POST PULLER

James Tarence Sanders, Pacific, Mo.

Application June 14, 1944, Serial No. 540,348

1 Claim. (Cl. 254—132)

The present invention relates to new and useful improvements in pullers, particularly for steel posts, and has for one of its important objects to provide, in a manner as hereinafter set forth, a manually operable device of this character comprising unique means for firmly gripping the post at any point in its length.

Another very important object of the invention is to provide a puller of the aforementioned character which is adapted to accommodate various sizes of steel posts.

Other objects of the invention are to provide a post puller of the character described which will be comparatively simple in construction, strong, durable, highly efficient and reliable in use, compact and which may be manufactured at low cost.

All of the foregoing, and still further objects and advantages of the invention, will become apparent from a study of the following specification, taken in connection with the accompanying drawings wherein like characters of reference designate corresponding parts throughout the several views, and wherein:

Figure 1 is a view in side elevation of a post puller constructed in accordance with the present invention.

Figure 2 is a top plan view of the device.

Figure 3 is a fragmentary view in vertical section, taken substantially on the line 3—3 of Figure 2.

Figure 4 is a view in front elevation of the device.

Figure 5 is a detail view in perspective of the swinging outer jaw.

Figure 6 is a cross sectional view, taken substantially on the line 6—6 of Figure 3.

Figure 7 is a sectional view taken substantially along the line 7—7 of Figure 5, as viewed in the direction indicated by the arrows.

Referring now to the drawings in detail, it will be seen that the embodiment of the invention which has been illustrated comprises a metallic stand which is designated generally by reference character 1. The stand 1 includes a pair of vertical metallic bars 2 which are secured together by rivets 3. At their lower ends, the bars 2 terminate in out-turned feet 4 which are secured by rivets 5 on a substantially triangular base 6. The bars 2 further include laterally offset, spaced upper end portions 7.

Journalized at an intermediate point on a bolt 8 between the upper end portions 7 of the bars 2 is a tubular metallic lever 9. Mounted in the rear end portion of the tubular lever 9 is an op-

erating handle 10. The forward end portion 11 of the tubular lever 9 is substantially square in transverse section.

The square forward end portion 11 of the tubular lever 9 is for the reception of a pair of spaced, forwardly projecting, downwardly curved metallic arms 12. A spacer 13 is provided between the arms 12 in the square portion 11 of the member 9. A rivet 14 anchors the members 12 and 13 in the lever 9. The members 12 and 13 are further secured in the lever 9 by welding, as at 15.

Pivotedly suspended between the spaced forward end portions of the arms 12 is a metallic link 16. An inner jaw 17 is mounted for swinging movement on the link 16. The jaw 17 comprises a pair of spaced members 18 between which the link 16 is pivotally secured by a bolt 19. The jaw 17 further includes a spacer 20 between the members 18. Rivets 21 secure the members 18 and 20 together. The jaw 17 still further includes, on the members 18 and 20, an arcuate, toothed or knurled post-engaging face 22.

Mounted for swinging movement on the jaw 17 and cooperable therewith is an outer jaw 23. A bolt 24 pivotally secures the outer jaw 23 on one side of the inner jaw 17. The jaw 23 includes a hook or the like 25 having a knurled or roughened face which is engageable with the post.

It is thought that the manner in which the device is used will be readily apparent from a consideration of the foregoing. Briefly, the stand 1 is placed on the ground adjacent the post to be pulled. The jaws 17 and 23 are then swung forwardly and upwardly substantially as suggested in dotted lines in Figure 3 of the drawings and the post is engaged therebetween. The handle 10 is then swung upwardly to lower the jaws 17 and 23 on the post. The construction and arrangement is such as to permit the jaws to readily slide downwardly on the post. However, when the handle 10 is swung downwardly, the jaws 17 and 23 firmly grip the post therebetween for elevating same. When the handle 10 is swung upwardly again, the jaws 17 and 23 release the post and slide downwardly thereon to permit a new grip to be obtained. A bolt 26 pivotally secures the link 16 between the arms 12.

It is believed that the many advantages of a post puller constructed in accordance with the present invention will be readily understood, and although a preferred embodiment of the device is as illustrated and described, it is to be understood that changes in the details of construction may be resorted to which will fall within the scope of the invention as claimed.

What is claimed is:

A post puller of the character described comprising a stand, a tubular lever pivotally mounted, at an intermediate point, for vertical swinging movement on said stand, an operating handle mounted in one end portion of the lever, a pair of spaced arms mounted in the other end portion of said lever, a link pivotally mounted between said arms, an inner jaw mounted for swinging movement on the link, said inner jaw including

10

a pair of spaced members straddling one end portion of the link and pivotally connected thereto, said inner jaw further including a spacer between the members, and an outer jaw pivotally mounted on the inner jaw and cooperable therewith for gripping a post therebetween for operatively connecting the lever thereto, said outer jaw including a hook engageable with the post.

JAMES TARENCE SANDERS.
